US00D553620S

(12) **United States Design Patent** (10) **Patent No.:** **US D553,620 S**
(45) **Date of Patent:** **** Oct. 23, 2007**

(54) **INPUT DEVICE FOR
COMPUTER-CONTROLLED SYSTEMS**

(75) Inventor: **Michael Schroeder**, Turkheim (DE)

(73) Assignee: **3 Dconnexion GmbH**, Seefeld (DE)

(**) Term: **14 Years**

(21) Appl. No.: **29/229,126**

(22) Filed: **May 3, 2005**

(30) **Foreign Application Priority Data**

Nov. 4, 2004 (EM) 000250071-0001/-0009

(51) **LOC (8) Cl.** **14-02**

(52) **U.S. Cl.** **D14/402; D14/217; D14/399**

(58) **Field of Classification Search** D14/399-417,
D14/217, 496; 273/148 B, 148 A; 345/156-167,
345/905; 74/71 XY; 463/1, 36-38, 46,
463/47; 200/5 R, 5 A, 6 A, 6 R

See application file for complete search history.

(57) **CLAIM**

The ornamental design for an input device for computer-controlled systems, as shown and described.

DESCRIPTION

FIG. 1 is a perspective view of an input device for computer-controlled systems showing my new design;

FIG. 2 is a top plan view thereof;

FIG. 3 is a right side elevational view thereof;

FIG. 4 is a bottom plan view thereof;

FIG. 5 is a top plan view thereof; and,

FIG. 6 is a left side elevational view thereof.

1 Claim, 5 Drawing Sheets

FIG. 1

FIG. 2***FIG. 3******FIG. 4******FIG. 5******FIG. 6***
